DESIGN FOR A COMBINED TIE-CLIP AND NAIL FILE

Jacob M. Weiss, Brooklyn, N. Y., assignor to Milton J. Bernstein, Brooklyn, N. Y.

Application October 16, 1940, Serial No. 95,879

Term of patent 3½ years

To all whom it may concern:

Be it known that I, Jacob M. Weiss, a citizen of the United States, residing at 1558 54th Street, in the Borough of Brooklyn, county of Kings, city and State of New York, have invented a new, original, and ornamental Design for a Combined Tie-Clip and Nail File, of which the following is a specification, reference being had to the accompanying drawing, forming part thereof.

Fig. 1 is a front elevational view, and

Fig. 2 is a side elevational view of a combined tie-clip and nail file in a closed position, showing my new design; and

Fig. 3 is a rear elevational view of the design, showing the nail file withdrawn from its casing.

I claim:

The ornamental design for a combined tie-clip and nail file, substantially as shown and described.

JACOB M. WEISS.
